UNITED STATES PATENT OFFICE.

MARINUS J. C. NYBORG, OF MINNEAPOLIS, MINNESOTA.

SEWING-NEEDLE.

No. 897,700.

Specification of Letters Patent.

Patented Sept. 1, 1902.

Application filed December 20, 1901. Serial No. 408,000.

To all whom it may concern:

Be it known that I, MARINUS J. C. NYBORG, a citizen of the United States, residing at the city of Minneapolis, in the county of Hennepin and State of Minnesota, have made certain new and useful Improvements or an Invention in Sewing-Needles; and I do hereby declare that the following is a full, clear, and exact description of the invention, which will enable others to use the same.

The present invention relates to improvements in hand sewing needles, especially those styled self-threading needles; and the objects in view are:—First, the provision of means for preventing the friction or wear upon that portion of the thread that is attached to or in contact with the needle during the operation of stitching; second, the provision of means for preventing, obviating or necessitating the thread being passed endwise through a transverse eye or channel for the thread to be attached to the needle; third, the provision of means for obviating or preventing the needle from slipping or gliding upon the thread when once threaded.

The invention consists in certain novel construction, combinations and arrangements of parts, as will hereinafter be fully described and claimed. This kind and style of needle being formed of steel or material capable of springing or giving slightly in its organic structure.

This needle is designed for tailoring purposes, although it is of course within the scope of the invention to employ the same for any of the common purposes for which a needle may be used, and many slight alterations from the detailed structure of the needle may be used and employed within the spirit and scope of the present invention. These objects are obtained by the employment of a needle comprising a main body portion formed with two separate same sized cylindrical channels entering at the head end and on either side of the center of the needle, leaving a thin fin or partition between them, and passing longitudinally with the center line of the needle for a desired distance to meet and emerge into a larger cylindrical channel which passes slantingly and towards the point end of the needle from the side of the needle in the plane of the fin or partition, and provided with two narrow parallel longitudinal open ended slots formed on the side of the needle directly between the emergence of the larger cylindrical channel

and the head end of the needle leaving the fin or partition between the said two slots.

In the accompanying drawings.—Figure 1, is a plan view of this form of needle; Fig. 2, 60 is a similar view, showing a thread in position for sewing; Fig. 3, is a side view of the needle, minus the point end of the same, showing the internal arrangement of the threading mechanism by dotted lines; Fig. 4, 65 represents a perspective view of the needle, minus the point end of the same, embodying the organic structure and features of the present invention.

Throughout the several views, like numbers refer to like parts.

The needle shown is of the same general form or shape as the ordinary common needle, except as to the shape or form of the head.

The head or threading mechanism which is the essential part of my invention is best shown in Fig. 4 in which numerals 1 and 2 indicate two separate cylindrical channels of the same size, running parallel with and on either side of the center of the needle, leaving a thin fin or partition 4 between them for a short distance from the head of the needle. Said channels 1 and 2 at this point intersect with a larger cylindrical channel 3 which runs longitudinally of the needle for a short distance along the center and then emerges from the side of the needle in the same plane as the fin or partition 4, and in a direction at an angle to the axis of the needle slanting 90 away from this axis and away from the head of the needle, as is best shown in Fig. 3. By cutting two narrow parallel open ended slots through the shell of the needle from this point of emergence of the channel 3 to the head of the needle, one connecting channel 1 and the other channel 2 with the surface of the needle and by removing the top portion of the remaining fin or partition 4, the channels 1 and 2 are connected in such a manner that a thread can be drawn into them without inserting the end thereof, as will be hereafter described.

At the point of intersection of the two same sized cylindrical channels, and the larger cylindrical channel 3 the channel 3 extends toward the point of the needle in such a manner as to cut away the lower portion of this fin or partition a short distance from the bottom of channels 1 and 2 forming a recess, as is best shown in Fig. 3, into which recess the thread will be drawn, and leaving

hook 5 which tends to hold the thread in said recess. As is shown best in Fig. 1 and Fig. 2, hook 5 is bent over to meet opposite side of channel 1 to form a spring which tends to 5 guide the thread into channel 2 when threading.

It is obvious from the reading of the preceding paragraphs, that the hook 5, is formed integral with the fin or partition 4, a slight portion throughout the length on the outside of the hook or spring is cut away leaving the hook or spring within the walls of the needle to prevent the same from lacerating or tearing the material when in operation of stitching. The hook or spring is sufficiently tapered throughout the length of same on the edge opposite the edge 6 of the needle shell, in such manner as to present a guiding surface for the thread to be readily attached to 20 the needle. I also desire to inwardly taper the edge 6 and edge 7 of the needle shell throughout the length of the slots to present a smooth and guiding surface for threading the needle.

25 The manner of threading this form of needle is to first draw the thread into channel 1 by passing it between the guiding surface of the partition 4 and the edge 6 of the needle-shell by a movement toward the point of the 30 needle until it passes below the hook or spring 5, then by reversing the motion and drawing the thread between the spring 5 and the edge 7 of the needle-shell until it has

been drawn into channel 2 and out of the end of the needle, thus securely holding the 35 thread by doubling it around and under hook or spring 5. Hence, the two portions of the thread are brought into two parallel planes with the main body of the needle and extend out of the head end of the needle, one 40 section of the thread extends out of said cylindrical channel 1, and the other section of the thread extends out of cylindrical channel 2, and by this process the needle is 45 threaded.

Having thus described my invention, what I claim and desire to secure by Letters Patent, is:—

A needle comprising a main body portion, formed with two longitudinal channels merging into a larger channel which passes slantingly towards the point end of the needle and emerges from the side of the needle, and provided with a tapered, bent hook or spring formed integral with said main body and having two inwardly tapering open ended parallel slots formed in the walls of the needle, substantially as described.

In testimony whereof, I have hereunto set my hand in the presence of two subscribing witnesses,

MARINUS J. C. NYBORG.
